UNITED STATES PATENT OFFICE.

FRANK A. GARBUTT, OF LOS ANGELES, CALIFORNIA.

BED.

Application filed October 15, 1919. Serial No. 330,861.

To all whom it may concern:

Be it known that I, FRANK A. GARBUTT, a citizen of the United States, residing in Los Angeles, Los Angeles County, California, have invented a new and useful Improvement Comprising a Bed, of which the following is a specification.

My invention relates to beds and an object of the invention is to provide a bed which will greatly add to the comfort of the person using it.

Further objects and advantages will be set forth more in detail hereinafter.

Referring to the drawings which are for illustrative purposes only.

Fig. 1 is a plan view of the spring structure certain portions being omitted for the sake of clearness of illustration.

Fig. 2 is a section on a plane represented by the line 2—2 of Fig. 1.

Fig. 3 is a section on a plane represented by the line 3—3 of Fig. 1.

Fig. 4 is an enlarged view of one of the plungers in a partly compressed position.

Fig. 5 is a view of a spring head.

Fig. 6 is a view of a rigid head.

In this form of spring, a box 50 is provided, this box having slats 51 across the top and slats 52 across the bottom. Sliding freely in holes in the slats 51 and 52 are a series of stems 53 each of these stems having a head 54. The head 54 may be formed of wire bent into a spiral as shown in Figs. 1 to 5 inclusive, or it may be of solid material as shown at 55 in Fig. 6. Rigidly secured on each of the stems 53 is a washer 56 which is engaged by a spiral compression spring 57. The tension of these compression springs can be adjusted by a series of wedges 58 which are secured to a strip 59, so that they can be manipulated from outside the bed through a convenient opening. The heads 54 are placed quite close together as shown in Fig. 1 for the purpose of supporting the mattress.

I claim as my invention:

1. In a bed: a plurality of plungers, each including a stem and a head on the upper end of said stem; means for mounting the stems of said plungers for axial movement; elastic means for resisting the movement of each plunger; and means for adjusting the tension of the elastic means of a plurality of said plungers together.

2. In a bed a plurality of plungers each 55 comprising a head; a stem to which said head is elastically secured; means for guiding said stem to prevent all movement of said stem except along the axis of said stem, said stem being free to move along 60 said axis; and elastic means for resisting movement along said axis.

3. In a bed a plurality of plungers each comprising a head; a stem to which said head is elastically secured; means for guiding 65 said stem to prevent all movement of said stem except along the axis of said stem, said stem being free to move along said axis; elastic means for resisting movement along said axis; and means for adjusting the 70 strength of said elastic means.

4. In a bed: a plurality of plungers, each including a stem and a head on the upper end of said stem; means for mounting the stems of said plungers for axial movement; 75 elastic means for resisting the movement of each plunger; a plurality of slidably mounted strips, each extending under a plurality of said plunger stems; and a plurality of wedges on each of said strips for engaging 80 the lower ends of the plungers over said strips upon movement of said strips, whereby the tension of said elastic means is adjusted.

5. In a bed, the combination of a plurality of plungers each comprising: a head; a stem to which said head is secured; means for guiding said stem to prevent all movement except along the axis of said stem, said 85 stem being free to move along the axis of said stem; a positive stop for limiting the upward movement of said stem; a spring forcing said stem against said stop; and means for adjusting the tension of said 90 spring without effecting the vertical position 95 of said head.

6. In a bed: a plurality of plungers, each including a stem and a head on the upper end of said stem; means for mounting the stems of said plungers for axial movement; 100 elastic means for resisting the movement of each plunger; and means operable from the outside of the bed for adjusting the tension of said elastic means.

In testimony whereof, I have hereunto set 105 my hand at Los Angeles, California, this 9th day of October, 1919.

FRANK A. GARBUTT.
